Primary Examiner—Jeffrey Asch

(74) Attorney, Agent, or Firm—Lawrence S. Cohen

(57) **CLAIM**

The ornamental design for a telephone body and keypad, as shown and described.

DESCRIPTION

FIG. 1 is a front elevation view.

FIG. 2 is a right side elevation view.

FIG. 3 is a rear elevation view.

FIG. 4 is a left side elevation view.

FIG. 5 is a top view; and,

FIG. 6 is a bottom view.

The broken line showings of a crank, handset, cradle, cord, and ornamentation on the body are for illustrative purposes only and form no part of the claimed invention.
